SPRINKLER

Howard Meuche, R.R. 1, Fort Branch, Ind.

Filed June 19, 1961, Ser. No. 65,643

Term of patent 7 years

(Cl. D91—1)

FIG. 1 is a perspective view of a sprinkler embodying my new design,

FIG. 2 is a side elevation thereof, and

FIG. 3 is a top plan view thereof.

I claim:

The ornamental design for a sprinkler, substantially as shown.
